J. McCORMICK

GATE

Filed Sept. 11, 1922

INVENTOR

BY *E.H. Bond*
ATTORNEY

UNITED STATES PATENT OFFICE.

JOHN McCORMICK, OF OTTAWA, ONTARIO, CANADA.

GATE.

Application filed September 11, 1922. Serial No. 587,625.

To all whom it may concern:

Be it known that I, JOHN McCORMICK, a citizen of the Dominion of Canada, and resident of Ottawa, in the county of Carleton and Province of Ontario, Dominion of Canada, have invented certain new and useful Improvements in Gates, of which the following is a specification.

This invention has relation to certain new and useful improvements in gate structures and has for its primary object the provision of a gate structure which will be of simple and inexpensive construction and which may be readily opened, if desired, from a distance when approaching the gate from either side thereof.

The invention has for another object the provision of a gate which will be automatically locked when closed but which may be readily unlocked or unlatched and opened by the operation of a single rock shaft controlled by levers on opposite ends thereof at a considerable distance from either side of the gate.

A further object of the invention resides in the provision of a gate of the character stated, which will be of such construction that the longitudinal bars thereof will swing on their rear ends and move toward and away from one another at their forward ends as the gate is opened and closed.

The invention has for a further object the provision of a gate of the character stated in which will be included a novel form of latch releasing mechanism connected with and controlled by the rock shaft carrying the gate lifting or opening members, so that the gate latch will be thrown into inoperative position at the beginning of the operation of the rock shaft which opens the gate.

The invention has for a still further object the provision of a gate of the character set forth, which will be composed of the minimum number of parts of simple and inexpensive construction and arrangement, which will be strong and substantial, highly efficient in use and which will include a balancing member adjustably mounted on the gate.

With the foregoing and other objects in view, as will appear as the description proceeds, the invention consists in the novel construction, combination and arrangement of co-operating elements as hereinafter more specifically set forth, claimed and shown in the accompanying drawings forming a part of the present application, in which:

Fig. 1 is an elevation of the improved gate in closed position, the gate being indicated in partially open position by dotted lines.

Fig. 2 is a plan view of the gate in closed position.

Referring more in detail to the drawings, in which similar reference characters designate corresponding parts throughout the several views, 5 indicates the latch carrying gate post which is slotted longitudinally and carries the link 6 which is of substantially U-shaped form and pivotally mounted at the free ends of its legs on the pivot members 7 projecting from the opposite sides of the latch carrying gate post 5 near the upper end thereof. The depending latch member 8 is carried in the projecting bight portion of the link 6, on the side of the latch carrying gate post 5 away from the gate opening.

When the gate is in closed position, the lower inwardly directed end of the depending latch member 8 engages upon the upper face of the projecting forward end 9 of one of the longitudinal gate bars 10, preferably the central bar, as shown in Fig. 1. The projecting forward end 9 of this longitudinal gate bar 10 extends through the latch carrying gate post 5 when the gate is in closed position.

A substantially U-shaped bracing member 11 is extended over the upper portion of the latch carrying gate post 5 and mounted on the pivot members 12 on opposite sides thereof. It will therefore be seen that while the substantially U-shaped bracing member 11 serves to brace the latch carrying gate post 5, it will not interfere with opening and closing of the gate, as the substantially U-shaped bracing member 11 may be turned away from the gate, as shown in the drawings.

The gate post 13 is located at the other

side of the gate opening and is anchored in upright position, as will be seen by referring to Fig. 1. The inclined gate carrying post 14 is connected at its upper end to the upright gate post 13, as shown in the drawings and extends downwardly and forwardly from one side thereof, as will be readily understood by referring to Fig. 1. The inclined gate carrying post 14 is formed of parallel spaced members connected at their upper ends by the connecting bolt 15.

The connecting members 16 extended through the forward end of the horizontal post bracing member 17 are also extended through the lower portions of the spaced members forming the inclined gate carrying post 14. Suitable connecting members 18 are passed through the rear end of the horizontal post bracing member 17 and into the lower portion of the gate post 13, as shown clearly in Fig. 1. It is therefore evident that the horizontal post bracing member 17 serves to connect and firmly brace the gate post 13 and the inclined gate carrying post 14.

The several longitudinal gate bars 10 are mounted on their respective pivot bolts 19 which extend through the rear ends of the longitudinal gate bars 10 and through the spaced members of the inclined gate carrying post 14 to permit the longitudinal gate bars 10 to swing in a vertical plan from the inclined gate carrying post 14. The several longitudinal gate bars 10 are connected near their forward ends by the parallel connecting bars 20 positioned on opposite sides of the gate and extending downwardly and forwardly with the lower ends of said parallel connecting bars 20 depending below the bottom or lowermost longitudinal gate bar 10. Pivot bolts 21 are extended through the parallel connecting bars 20 and through the respective longitudinal gate bars 10, as shown in the drawings. By referring to Fig. 1, it will be evident that the parallel connecting bars 20 permit the longitudinal gate bars 10 to swing freely on their respective pivot bolts 19 and as the gate swings upwardly, the forward free ends of the longitudinal gate bars 10 will move closer together, as indicated by dotted lines.

The reinforcing plates 22 are secured upon the sides of the lowermost longitudinal gate bar 10 at the rear end thereof, as shown clearly in Fig. 1. Similar reinforcing plates 23 are secured on the sides of the uppermost longitudinal gate bar 10 and mounted on the gate operating shaft 24 extended transversely through the inclined gate carrying post 14 in place of a pivot bolt 19 for this uppermost longitudinal gate bar 10. The rear end of the uppermost longitudinal gate bar 10 is cut away, as shown in Fig. 1 and the purpose of which will presently appear.

By referring to Fig. 2, it will be seen that the gate operating shaft 24 extends for some distance to either side of the gate and then terminates in downwardly directed operating ends 25. It will also be seen by referring to Fig. 2 that the reinforcing plates 23 have their main portions offset outwardly from the sides of the longitudinal gate bars 10 and positioned outwardly of the sides of the inclined gate carrying post 14. This is also true of the reinforcing plates 22, as shown in Fig. 2.

Rigidly mounted on the centre of the gate operating shaft 24 is the upwardly and rearwardly directed lever arm 26, to the upper end of which is pivotally connected one end of the rod 27, the other or forward end of which is pivotally connected to the upper end of the latch releasing finger 28. This latch releasing finger 28 is mounted on the pivot bolt 29 provided therefor in the forward end portion of the uppermost longitudinal gate bar 10, while the downwardly and outwardly directed lower end 30 of the latch releasing finger 28 works freely through the latch carrying gate post 5. This downwardly and outwardly directed lower end 30 of the latch releasing finger 28 engages the inner side of the depending latch member 8 to force the same outwardly to inoperative position and release the gate when the latch releasing finger 28 is operated through the medium of the rod 27 and upwardly and rearwardly directed lever arm 26 when the gate operating shaft 24 is turned in one direction.

Rigidly mounted on the gate operating shaft 24, outwardly of the sides of the inclined gate carrying post 14 and adjacent the latter, are the gate raising members 31 which are inclined downwardly and forwardly and then extended forwardly in a horizontal plane, as shown clearly in Fig. 1. These gate raising members 31 terminate in turned forward free ends 32 directed toward one another and extending beneath the reinforcing plates 23 and normally spaced slightly below the same.

When turning of the gate operating shaft 24 is continued after the releasing of the depending latch member 8 from the gate, the turned forward free ends 32 of the gate raising members 31 will contact with the reinforcing plates 23 and raise the gate to open position by swinging the longitudinal gate bars 10 upwardly on their pivotally mounted rear ends. This may be readily understood by reference to Fig. 1, in which the gate is shown by dotted lines in partially open position.

In order that the gate may be properly balanced at all times and opening and closing thereof more readily accomplished, a counterbalancing weight 33 is employed. This counterbalancing weight 33 is adjust-

ably mounted between the extended rear ends of the longitudinally slotted weight supporting bars 34 by means of the mounting members 35 adapted to be secured in 5 adjusted position along the slots of the longitudinally slotted weight supporting bars 34.

One of the central or inner longitudinal gate bars 10 carries the longitudinally slotted weight supporting bars 34 which are 10 slidably mounted on the pivot bolt 19 for said longitudinal gate bar 10 and a clamping nut 36 is employed on an additional guide bolt 37 projecting from one side of the 15 said longitudinal gate bar 10 and through the slots of the longitudinally slotted weight supporting bars 34, so that the latter may be securely fastened in adjusted position longitudinally of the longitudinal gate 20 bar 10.

It is evident that a fine adjustment of the counterbalancing weight 33 on the gate may be accomplished by adjustment of the counterbalancing weight 33 on the longitudinally 25 slotted weight supporting bars 34 and also adjustment of the latter on the longitudinal gate bar 10 supporting the same. Downward swinging movement of the gate is limited by means of a stop block 38 within 30 the latch carrying gate post 5.

From the foregoing paragraphs taken in connection with the accompanying drawings, the complete construction and operation should be apparent. It may be briefly stated, 35 however, that whenever the gate is closed, the depending latch member 8 will automatically engage the projecting forward end 9 of one of the longitudinal gate bars 10 and lock or latch the gate in closed position, as shown 40 in Fig. 1.

Whenever it is desired to open the gate when approaching the same from either direction, the downwardly directed operating end 25 of the gate operating shaft 24 on this 45 side of the gate is grasped and the gate operating shaft 24 rotated or turned in the proper direction to draw back the upwardly and rearwardly directed lever arm 26 and actuate the latch releasing finger 28 to disengage the depending latch member 8 and swing the same together with its link 6 on the pivot members 7 until the depending latch member 8 is in inoperative position, thereby completely releasing the gate. 50

As the movement of the gate operating shaft 24 in this direction is continued, the gate raising members 31 engage the reinforcing plates 23 and lift or raise the entire gate to open position. As the gate rises, the 55 counterbalancing weight 33 lowers, as indicated by dotted lines in Fig. 1.

When the gate is to be lowered or turned to closed position, the gate operating shaft 24 should be turned in the reverse direction by means of one of its downwardly directed

operating ends 25 and as the gate closes, the depending latch member 8 will automatically catch upon the projecting forward end 9 of one of the longitudinal gate bars 10 and again latch or lock the gate in closed position. 70

While the preferred embodiment of the invention has been disclosed, it is to be understood that minor changes in the details of construction, combination and arrangement of co-operating elements may be resorted to within the scope of what is claimed without departing from the spirit of the invention. 75

What I claim as new is: 80

1. A gate structure comprising a gate post; a second gate post; an inclined gate carrying post connected with the second mentioned gate post; a gate including parallel gate bars pivotally mounted in the inclined gate carrying post; inclined parallel connecting members pivoted to each of said gate bars; means for swinging the said gate bars on their rear ends to move the said bars toward and away from one another at their forward ends as the gate is opened and closed; a counterbalancing means mounted on one of said gate bars; a latch member carried by the first mentioned gate post and normally engaged with one of said gate bars to retain the gate in closed position; and means for releasing the gate from the latch member and swinging the gate upwardly to open position. 90

2. A gate structure comprising gate posts; a latch member carried by one of said gate bars; and having its free end engageable with the free end of one of the gate bars, a gate including gate bars pivotally mounted in one of said gate posts; inclined parallel means for pivotally connecting the free end portions of said gate bars; said free end portions of the gate bars being adapted to be received in the first mentioned gate post; said latch member being adapted for automatic engagement with one of the gate bars to lock the gate in closed position; means for swinging the gate in a vertical plane to open and closed positions; said last mentioned means extending for a considerable distance to either side of the gate structure; means for swinging the said gate bars on their rear ends to move the said bars toward and away from one another at their forward ends as the gate is opened and closed; latch releasing mechanism controlled by the last mentioned means; and a counterbalancing means adjustable on one of said gate bars. 115

3. A gate structure comprising a gate post, a second gate post, an inclined gate-carrying post connected with the second-mentioned gate post, a gate including gate bars pivoted at one end to said inclined post, a member parallel with said inclined post and pivotally connected to said bars, a latch pivoted on the 125 130

first named gate post with its free end engageable with the end of one of the gate bars, a reinforcing member secured to one of said bars, a gate-operating shaft on which 5 said member is mounted, said shaft terminating in downwardly directed ends, gate-raising members mounted rigidly on said shaft and extended to engage beneath said reinforcing member, a counterweight carried by the gate, and an arm on the said shaft and 10 connected with the said latch.

In testimony whereof, I affix my signature.

JOHN McCORMICK.
